Specification of Letters Patent.

Patented Oct. 30, 1917.

Application filed January 31, 1917. Serial No. 145,746.

BED.

To all whom it may concern:

Be it known that I, DIEDRICH STEFFEN, a citizen of the United States, residing at 43 Pomeroy ave., Kearney, in the county of 5 Hudson and State of New Jersey, have invented new and useful Improvements in Beds, of which the following is a specification.

This invention relates to beds, the object 10 in view being to provide a form of coupling in which means are employed for permitting the spring fabric to be conveniently placed under tension or the fabric tilted or canted whereby restful positions of the body 15 of the occupant of the bed may be effected, the latter being often desired and sometimes necessary when the bed is used by the sick in hospitals.

In the drawings forming a part of this 20 specification and in which like reference numerals indicate similar parts throughout the several views:—

Figure 1 is a side view of a portion of the bed with one of the side bars broken away. 25 Fig. 2 is a horizontal section through the corner of the bed.

Fig. 3 is a perspective view of a portion of the corner post.

Fig. 4 is a section on the line 4-4 of 30 Fig. 2.

Fig. 5 is a perspective view of a portion of the attaching bar of the spring fabric.

With a view to providing a bed which 35 will consist of mating or co-acting elements, relatively associated, whereby the side bars of the bed may be expeditiously separated from the head and foot pieces and the spring fabric tensioned or tilted at the desires of the operator, use is made of substantially identical corner posts 1, two of 40 such posts being employed in the construction of the head member A and a corresponding number being employed in the construction of the foot piece or member B.

45 Each of these corner posts has shrunk thereon or otherwise suitably secured thereto, a sleeve 2 having integral cylindrical stubs 3 and 4 which are arranged at right angles to one another. The stubs 3 of the 50 corner posts of the head and foot members are alined with each other and these stubs are provided with flat surfaces 5 which lead to short locking grooves 6 formed in said stubs as clearly shown in Fig. 3. The side 55 rails 7 of the bed structure are provided

over the flat surfaces 5 and then by simply turning said side rails in one direction upon the stubs 3, the pins are extended into the grooves 6 and said side rails are, in this manner, securely connected with the head 60 and foot members. The pins 8 are disposed within the ends of the side rails whereby to permit the stubs 3 to enter said rails as clearly shown in Fig. 2. The pins 8 are disposed at a tangent to the stubs with which 65 they are engaged and it is observed that by simply giving the side rails a partial turn, the pins may be brought almost immediately on to the flat surfaces 5 and the rails quickly and conveniently separated from the stubs. 70 The corner posts of each of the head and foot members are connected by end rails 9. These rails are identical in construction and each is adapted to be fitted at its ends on to the mating alined stubs 4. The said end 75 rails are also adapted to be revolved or turned upon said stubs and it is therefore desired to form in each stub, a circumferential groove 10. When the ends of the rails are associated with or fitted on the stubs 4, 80 pins 11 may be extended through said rails and through the grooves 10 at a tangent thereto. In this manner, the end rails are effectually held against longitudinal movement upon the stubs but are free to be re- 85 volved therearound.

As previously described, it is intended that aside from the novel knock-down features, I contemplate providing a bed in which the spring fabric may be tensioned or arranged 90 at an angle if desired, the latter being preferred in many cases, such as when the bed is used in hospitals and it is desired to change the position of the body of the patient or invalid at some particular time. In 95 view thereof, I mount sliding clutch elements 12 upon the stubs 4. These elements have longitudinal slots 13 therein in which fixed pins 14 upon the stubs 4 extend. Interposed between the clutch elements 12 and 100 the sleeves 2, are springs 15 which operate to yieldingly hold the clutch elements 12 in engagement with the fixed clutch elements 16 in the end rails. The elements 12 are each provided with a circular series of clutch 105 teeth 17 which, under the action of the springs 15 are adapted to engage similar clutch teeth 18 upon the fixed clutch elements 16. The clutch elements 16 are mounted upon the stubs 4 and while per- 110

mitted to turn thereon, the pins 11 prevent longitudinal movement thereof upon the stubs.

Fixed to each of the end rails are revolving arms 18 having substantially key holed shaped slots 19. The spring fabric 20 is provided at its ends with bars 21 to which the ends of the fabric are secured. These bars are provided at spaced intervals with substantially cylindrical enlargements 22 which are adapted to be seated in the corresponding branches of the key hole shaped slots 19. In this manner, it is seen that the bars are held against accidental derangement from the arms 18, irrespective of the adjustment of the end rails upon the corner posts. In applying the bars 21, the portions 22 are initially arranged at one side of the arms 18. The bars are then moved in a longitudinal direction through said arms until the portions 22 become seated in their receiving branches of the slots 19.

The structure, in its entirety, is simple, strong and durable. The side rails may be conveniently taken down as the occasion demands and at the will of the operator, the corner posts may be quickly disconnected from both the side and the end rails. When it is desired to tension the springs, the end rails are directed away from the end and foot members of the bed. The fixed clutch freely passes over the movable clutch elements and the desired tensioned adjustment of the spring fabric may, in this manner, be very nicely retained. The arrangement of the arms 18 upon the end rails is also such

as will permit the spring fabric to be canted or tilted as shown in dotted lines in Fig. 1. The means for shifting each clutch member 12 out of engagement with the respective clutch member 16 embodies a ring 23 surrounding the rail 9 and having studs 24 which extend through holes in said rail into an annular groove 25 in the clutch member 12 as in Fig. 2. By grasping the ring 23 the clutch member 12 may be shifted outwardly to permit the rail 12 to be turned.

What is claimed as new is:—

1. A bed having tubular end rails mounted for rocking movement, arms fast thereon, a spring fabric connected with said arms, and means for holding said rails against rocking movement embodying clutching means housed within said end rails.

2. A bed structure, comprising head and foot members, each member including vertical corner posts, side rails connecting the corner posts of the head member with the corner posts of the foot member, the corner posts of each member having aligned integral portions, clutch elements mounted thereon, end rails connecting said portions, clutch elements carried by the end rails and co-acting with the first clutch elements, arms fixedly mounted on the end rails, and a spring body between the arms of the end rail of the head member and the arms of the end rail of the foot member.

In testimony whereof I affix my signature.

DIEDRICH STEFFEN.
